US00D724278S

(12) **United States Design Patent**
Avalos Sartorio et al.

(10) **Patent No.:** **US D724,278 S**
(45) **Date of Patent:** **** Mar. 10, 2015**

(54) **FOOD PLATE FOR PETS**

(71) Applicants: **Miguel José Avalos Sartorio, Zapata (MX); Carlos José Avalos Sartorio, Zapata (MX)**

(72) Inventors: **Miguel José Avalos Sartorio, Zapata (MX); Carlos José Avalos Sartorio, Zapata (MX)**

(**) Term: **14 Years**

(21) Appl. No.: **29/499,860**

(22) Filed: **Aug. 19, 2014**

(30) **Foreign Application Priority Data**

Mar. 12, 2014 (MX) MX/f/2014/000835

(51) **LOC (10) Cl.** **30-03**

(52) **U.S. Cl.**

USPC **D30/130**

(58) **Field of Classification Search**

USPC D30/121, 129–132; 119/51.5, 61.5, 119/51.54; D1/124; D7/553.8, 555, 556; D9/609, 643

See application file for complete search history.

(57) **CLAIM**

The ornamental design for a food plate for pets, as shown and described.

DESCRIPTION

FIG. 1 is a perspective view of the food plate for pets showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

1 Claim, 7 Drawing Sheets
